(57) **CLAIM**

The ornamental design for an intelligent robot, as shown and described.

DESCRIPTION

FIG. 1 is a front view of an intelligent robot in accordance with the present new design;

FIG. 2 is a rear view of the intelligent robot design;

FIG. 3 is a top view of the intelligent robot design;

FIG. 4 is a bottom view of the intelligent robot design; and,

FIG. 5 is a left view of the intelligent robot design; and,

FIG. 6 is a right view of the intelligent robot design.

The broken lines in the drawings depict unclaimed environmental subject matter.
